SINGLE PISTON GAS METER

Gompei Kuwada, Maedani-mura, Kawabe-gun,
JapanApplication March 31, 1936, Serial No. 71,967
In Japan April 19, 1935

14 Claims. (Cl. 73—237)

This invention relates to a single piston gas meter.

The object of my invention is to provide a gas meter in which the prime mover is a single piston, designed to avoid in its construction the usual diaphragm and its inherent source of error.

The presently preferred embodiment of my invention is shown in the accompanying drawings, 10 in which

Fig. 1 is a horizontal sectional view of a single piston gas meter embodying the present invention and showing the valve mechanism in plan view.

Fig. 2 is a vertical sectional view on line 2—2 of Fig. 1.

Fig. 3 is a vertical sectional view through the valve-operating mechanism, the same being taken substantially on line 3—3 of Fig. 1.

Fig. 4 is an enlarged face view of one of the cams for actuating the slide valves.

Fig. 5 is a detail sectional view showing the manner in which the slide valve-actuating lugs are secured to the valve rods.

Fig. 6 is a plan view of the end of one of the valve rods which carries the actuating lug.

Fig. 7 is a side view showing the operative connection between a part of the register-actuating mechanism and the bell rod.

Fig. 8 is a vertical sectional view on line 8—8 of Fig. 7, and

Fig. 9 is a plan view of the parts shown in Fig. 7.

In the drawings, a gas-receiving bell 1 has a rod 2 extending upwardly therefrom and guided in its vertical movement by a bracket 3. At an intermediate point the rod 2 carries a pivoted crosshead 4 which has a bore 4'. The crosshead 4 is provided with journals on its opposite sides which are received in bearings in the sides of a box formed by an enlargement on the bell rod 2. The bore 4' extends at right angles to the journals about which the crosshead 4 pivots and receives one end of a pivoted lever 5 having an extension 6 for supporting a counterweight 7 for the bell 1.

The upper portion of the bell rod has a bracket 8 rigidly secured thereto. At opposite sides the bracket 8 carries cam blocks 9 and 10 for actuating slide valves 11 and 12 which respectively control the admission of gas to and its exhaust from the meter. Each cam block has a cam groove 13 for receiving lugs 14 rigidly secured to rods 15 and 16 for actuating the gas

admission and exhaust valves 11 and 12, respectively.

As shown in Fig. 4, the cam grooves 13 are generally oval in shape, as are also the lugs 14. In order that the lugs 14 will travel upwardly on one side and downwardly on the other side of the oval groove and thereby impart reciprocatory motion to the slide valves 11 and 12 as the cams rise and fall, they are set at an angle to the vertical corresponding to the curve at the upper and lower parts of the oval grooves of the cams. The angle at which the lugs 14 are set is toward the right on the admission valve side, (Fig. 4) and toward the left on the exhaust valve side.

To rigidly secure the lugs 14 in their preferred angular position, each lug, as shown in Figs. 5 and 6, is provided with a shank 17 which is received within its respective valve rod, and a threaded stud 18 for receiving a nut 19. The shanks 17 carry pins 20 which fit into slots 21 in one side of the valve rods and hold the lug in proper angular position with respect to the oval grooves 13.

The oval grooves 13 are so dimensioned that their major axis is equal to the length of the stroke of the bell 1 and its rod 2, and its minor axis is equal to the length of the stroke which the slide valves 11 and 12 are to have.

Each cam block is provided with upper and lower curved slots 22 and 23 which open into the oval grooves 13. Curved flat springs 24 and 25 have one end secured in the slots 22 and 23. The major portion of the springs 24 and 25 extend into the oval grooves. As shown in Fig. 4, the springs are of sufficient length to extend substantially the entire length of the groove, and their free ends are so curved with respect to the groove that when the lugs reach the upper or lower extremities of the groove, the curved free ends of the springs will snap them sidewise into the opposite side of the groove.

The slide valve 11 cooperates with an admission valve body 26 having a seat over which the valve slides. The valve body 26 has a central port 27 and side ports 28 and 29. The central port 27 communicates with a pipe 30 which supplies gas from the usual gas mains. The port 28 communicates with a pipe 31 which extends downwardly and then upwardly and has an open end communicating with the space inside the bell 1. The port 29 opens into the space above the bell 1. The slide valve 12 cooperates with an exhaust valve body 32 having a central and side ports similar to the valve body. A gas

exhaust pipe 33 leads from the center port while one side port communicates with the pipe 31 leading to the space within the bell 1, and the other side port opens into the space above the bell.

The valve rods 15 and 16 are provided with threaded portions 15' and 16', respectively, which pass through lugs 11' and 12', respectively, formed on the top of the slide valves 11 and 12. Adjustment nuts are threaded onto the threaded portions of the valve rods at opposite sides of the lugs, so that the position of the valves 11 and 12 may readily be adjusted with respect to the valve bodies 26 and 32, respectively.

The bell 1 is mounted for vertical movement in an oil seal container 34, the top 35 of which has an opening 36, so that when the bell rises, gas within the oil container may be forced through the opening 36 into the main portion of the gas-tight meter casing 37. An amount of oil sufficient to keep the lower end of the bell 1 submerged at all times is maintained in the bottom of the container 34.

The oil seal container 34 is so shaped that its bottom is raised up in the form of an inverted cup to correspond to the inside of the bell 1, and the top is drawn down, like the neck of an inverted bottle, around the central opening 36, to prevent the flow of the sealing oil to the outside of the container, in case the meter should accidentally be tilted or inverted.

Even though relatively heavy oil is used as the sealing medium, a small amount might, after an extended period of use, be carried over with the passing gas. However, such passing over of a small quantity of the oil will not affect the measuring capacity of the meter, as the displacement is determined by the fixed length of the stroke of the bell.

The meters will of course be installed with the inlet to the gas admission valve body 26, and the outlet from the gas exhaust body 32, but should anyone unauthorizedly and for improper purposes reverse the connections, the meter will not pass gas, because when the bell is at the limit of its downward stroke, the relative position of the slide valve 11 to the admission valve body 26 is such that due to the position of the bell, no gas can be exhausted from below the bell through the central port 27 and the pipe 30. Thus, the possibility of running the meter in reverse after a certain amount has been registered on the register, is precluded.

The pivoted lever 5 is rigidly secured to an axle 38, mounted in a bracket 39. A crank 40 is rigidly secured to one end of the axle and through a connecting link 41 and a pawl 42, mounted upon a pivoted lever 43, operates a ratchet wheel 44, of a counter 45, visible through a window 46 of the meter casing. The lever 43 has its fulcrum on the axis of the ratchet wheel 44.

The operation of my invention is as follows:

Assuming the parts to be in the position shown in Figs. 1 and 2, that is, with the admission slide valve 11 moved to the extreme left so that gas from the gas inlet pipe 30 communicates, through the central port 27 and side port 28, with the pipe 31, and the bell 1 is rising. As the bell continues to rise, the cam block 9 will continue also to rise until the lug 14 is in the lower portion of the oval groove 13. Simultaneously with the rising of the bell and the cam block 9, the lug 14, the rod 15 and the admission slide valve 11, were being moved by the cam groove, to the

right, that is, to a position such that the valve 11 will cut off communication between the gas inlet pipe 30 and the pipe 31 leading to the space beneath the bell, and establish communication between the gas inlet pipe 30 and the space above the bell. The movement of the valve 11 with respect to the ports 27, 28, and 29 is so correlated with respect to the shape of the cam groove, that just before the valve 11 moves to the right sufficiently to cut off communication between the central port and the port 28, the lug 14 reaches the lowermost part of the groove 13, and the free end of the spring 24 snaps the lug to the right sufficiently to throw it into the right-hand side of the groove 13. Simultaneously, the valve 11 also was moved past its dead-center position with respect to the side ports 28 and 29, and to that position in which communication is established between the central port 27 and the side port 29. Gas from the inlet main 30 then flows into the space above the bell 1 and creates a pressure sufficient to force the bell and cam downward until the valve-actuating lug 14 is in the uppermost part of the groove 13, and valve 11 is just about to cut off communication between the central port 27 and the space above the bell. The spring 25 then acts to snap the lug 14 to the left, and into the left-hand side of the groove 13, and simultaneously move the valve 11 past its dead-center position and again establish communication between the gas inlet pipe and the space beneath the bell.

The operation of the valve 12 is the same as that of the valve 11, except that they move in opposite directions; that is, while the lug for operating the slide valve rod 15 of the admission valve is operating in the left-hand groove of the cam, the lug for the slide valve rod 16 of the exhaust valve will be operating in the right-hand groove of the cam. Thus, when the valve 11 moves to its right-hand position to admit gas into the space above the bell, valve 12 will move to the left, and the gas beneath the bell is forced back through pipe 31 and through the left-side port and central port of the valve body 32, to the gas exhaust pipe 33. In like manner, when the valve 11 again moves to the position shown in Fig. 2, and the bell 1 is rising under the pressure of the gas from the supply main, gas in the space above the bell is forced through the right side port and central port of the valve body 32 to the gas exhaust pipe 33. In that way, gas is admitted alternately inside and outside of the bell, thus permitting a continuous flow of gas through the meter.

As the bell rises and falls during operation of the meter, the lever 5 and the axle on which it is mounted will be oscillated, and the pawl 42 caused to rotate the ratchet wheel 44, to register on the counter 45 the exact amount of gas passing through the meter.

The invention has been illustrated and described in connection with a preferred embodiment thereof, but it is to be understood that the same is not limited to the embodiment shown, and that various changes within the scope of the appended claims may be made without departing from the spirit of the invention.

I claim:

1. A single-piston gas meter comprising an actuating member reciprocable by gas pressure, a cam-actuating rod movable by said member, a gas-admission valve adapted to be connected to a source of gas under pressure, a gas exhaust valve, a pair of grooved cams movable by said rod, 75

- means for passing gas from said gas admission valve alternately to opposite sides of said actuating member to reciprocate the same, a reciprocating valve-actuating rod for the gas exhaust valve, a reciprocating valve-actuating rod for said gas admission valve adapted to operate said gas-admission valve to cause gas to be passed to one side or the other of said actuating member, means actuated by one of said cams for reciprocating the gas exhaust valve actuating rod, means actuated by the other of said cams for reciprocating the gas admission valve actuating rod, means operable when said valve rods approach either of their end positions for imparting movement to said valve rods independently of said cams, an indicator, a crosshead carried by the cam-actuating rod, and means operated by said cross head as the cam actuating rod reciprocates for actuating said indicator.
- 20 2. A single-piston gas meter comprising an actuating member reciprocable by gas pressure, a cam-actuating rod movable by said member, a gas-admission valve adapted to be connected to a source of gas under pressure, a gas exhaust valve, a pair of grooved cams movable by said rod, means for passing gas from said gas-admission valve alternately to opposite sides of said actuating member to reciprocate the same, a reciprocating valve-actuating rod for the gas exhaust valve, a reciprocating valve-actuating rod for said gas-admission valve adapted to operate said gas-admission valve to cause gas to be passed to one side or the other of said actuating member, a lug carried by the actuating rod for the gas-admission valve and positioned in the groove of one cam for actuating said admission-valve-actuating rod, a lug carried by the actuating rod for the gas exhaust valve and positioned in the groove of the other cam for operating said exhaust-valve-actuating rod, each of said lugs being oval in form and set at an angle to the vertical corresponding to the curve at the ends of the cam grooves, and means operable when said valve rods approach either of their end positions for imparting movement to said valve rods independently of said cams.
- 30 3. A single-piston gas meter comprising an actuating member reciprocable by gas pressure, a cam-actuating rod movable by said member, a gas-admission valve adapted to be connected to a source of gas under pressure, a gas exhaust valve, a pair of grooved cams movable by said rod, means for passing gas from said gas admission valve alternately to opposite sides of said actuating member to reciprocate the same, a reciprocating valve-actuating rod for the gas exhaust valve, a reciprocating valve-actuating rod for said gas-admission valve adapted to operate said gas-admission valve to cause gas to be passed to one side or the other of said actuating member, a lug carried by the actuating rod for the gas-admission valve and positioned in the groove of one cam for actuating said admission-valve-actuating rod, a lug carried by the actuating rod for the gas exhaust valve and positioned in the groove of the other cam for operating said exhaust-valve-actuating rod, each of said lugs being oval in form and set at an angle to the vertical corresponding to the curve at the ends of the cam grooves, and means operable when said valve rods approach either of their end positions for imparting movement to said valve rods independently of said cams.
- 40 4. A single-piston gas meter comprising an actuating member reciprocable by gas pressure, a cam-actuating rod movable by said member, a gas-admission valve adapted to be connected to a source of gas under pressure, a gas exhaust valve, a pair of grooved cams movable by said rod, means for passing gas from said gas admission valve alternately to opposite sides of said actuating member to reciprocate the same, a reciprocating valve-actuating rod for the gas exhaust valve, a reciprocating valve-actuating rod for said gas-admission valve adapted to operate said gas-admission valve to cause gas to be passed to one side or the other of said actuating member, a lug carried by the actuating rod for the gas-admission valve and positioned in the groove of one cam for actuating said admission-valve-actuating rod, a lug carried by the actuating rod for the gas exhaust valve and positioned in the groove of the other cam for operating said exhaust-valve-actuating rod, each of said lugs being oval in form and set at an angle to the vertical corresponding to the curve at the ends of the cam grooves and spring means operable when said valve rods approach either of their end positions for imparting movement to said valve rods independently of said cams.
- 50 5. A single piston gas meter comprising a bell, a bell rod fixed to said bell, a bracket fixed to said bell rod, a pair of cams carried by said bracket, a gas-admission valve body, a gas-exhaust valve body, a slide valve for controlling the passage of gas through each of said valve bodies, a valve rod for each of said slide valves, said valve rods being operable by said cams, a conduit connecting said valve bodies to the space beneath said bell, means for passing gas from said gas admission valve alternately to the space above said bell, and through said conduit to the space beneath said bell to impart a reciprocating movement to said bell, the gas beneath said bell being forced back through said conduit to the gas-exhaust valve body when said bell descends, spring means for imparting movement to said valve rods when they approach either of their end positions, a crosshead carried by said bell rod, a lever actuated by said crosshead as said bell reciprocates, an indicator, and means operated by said lever for actuating said indicator.
- 60 6. A single piston gas meter comprising a reciprocating bell, an oil seal container in which said bell reciprocates, a bell rod fixed to said bell, a crosshead carried by said bell rod, a lever operable by said crosshead as the bell reciprocates, an indicator operable by said lever, a counterweight for balancing said bell, a bracket fixed to said bell rod, a pair of cams having generally oval-shaped grooves carried by said bracket, a gas-admission valve body, a gas-exhaust valve body, a slide valve for controlling the flow of gas through each of said valve bodies, a valve rod for each of said slide valves, a conduit connecting said valve bodies to the space beneath said bell, the gas from the gas-admission valve body passing alternately to the space above said bell and through said conduit to the space beneath said bell, to reciprocate the bell, the gas beneath said bell being forced back through said conduit to the gas-exhaust valve body when the bell descends, each of said valve rods having lugs secured thereto and extending into the grooves in the respective cams, said lugs being oval in form and set at an angle to the vertical corresponding to the curve at the upper and lower extremes of the oval grooves, and curved flat springs in said oval grooves for imparting movement to said valve rods independently of said

cams when said valve rods approach either of their end positions.

7. A single piston gas meter comprising a bell, an oil-seal container for said bell, a bell rod fixed to said bell, a lever, a counterweight connected to said lever for balancing the bell, cams having generally oval-shaped grooves carried by said bell rod, lugs and valve rods actuated by said grooved cams, a pair of slide valves connected to 10 said valve rods, one for gas admission and the other for gas exhaust, an admission valve seat, an exhaust valve seat, a passage tube connecting the valve-seat ports to the space beneath said bell, and a crosshead consisting of a box formed 15 by an enlargement on the bell rod and a block mounted in said box and freely journaled on opposite sides of the box, said block having a bore through which said lever freely passes.

8. A single piston gas meter comprising a bell, 20 an oil-seal container for said bell, a bell rod fixed to said bell, a crosshead on said bell rod, a lever connected to said crosshead, a counterweight connected to said lever for balancing said bell, a bracket fixed to said bell rod, cams having generally oval-shaped grooves carried by said bracket, lugs positioned in said grooves and actuated by movement of said cams, means for moving said lugs into alternate sides of said grooves as they approach the ends of the grooves, valve rods 25 connected to said lugs and actuated thereby, slide valves connected to said valve rods, one for gas admission and the other for gas exhaust, an admission valve seat, an exhaust valve seat, a passage tube connecting the valve seat ports to the 30 space beneath said bell, the major axis of the grooves in said cams equaling the length of the stroke of the bell and the minor axis of said grooves equaling the length of the stroke of the slide valves.

40 9. A single piston gas meter comprising a bell, an oil-seal container for said bell, a bell rod fixed to said bell, a crosshead on said bell rod, a lever connected to said crosshead, a counterweight connected to said lever for balancing said bell, a bracket fixed to said bell rod, cams having generally oval-shaped grooves carried by said bracket, lugs positioned in said grooves and actuated by movement of said cams, means for moving said lugs into alternate sides of said grooves as they 45 approach the ends of the grooves, valve rods connected to said lugs and actuated thereby, slide valves connected to said valve rods, one for gas admission and the other for gas exhaust, an admission valve seat, an exhaust valve seat, a passage tube connecting the valve seat ports to the 50 space beneath said bell, each of said valve seats being provided with three ports, a central and two side ports, one of each of the side ports of each valve seat being connected to the tube leading to the space beneath the bell, the other side port of each valve seat opening to the space 55 above the bell and the central ports being connected to a gas admission passage and to a gas exhaust passage, the major axis of the grooves in said cams equaling the length of the stroke of the bell and the minor axis of said grooves equaling the length of the stroke of the slide valves.

10. A single piston gas meter comprising a bell, 70 an oil-seal container for said bell, a bell rod fixed to said bell, a crosshead on said bell rod, a lever connected to said cross-head, a counterweight connected to said lever for balancing said bell, a bracket fixed to said bell rod, cams having generally oval-shaped grooves carried by said bracket

et, lugs positioned in said grooves and actuated by movement of said cams, means for moving said lugs into alternate sides of said grooves as they approach the ends of the grooves, valve rods connected to said lugs and actuated thereby, slide 5 valves connected to said valve rods, one for gas admission and the other for gas exhaust, an admission valve seat, an exhaust valve seat, a passage tube connecting the valve seat ports to the space beneath said bell, the major axis of the 10 grooves in said cams equaling the length of the stroke of the bell and the minor axis of said grooves equaling the length of the stroke of the slide valves, the top of the oil-seal container being open at its middle and drawn down like a 15 neck of an inverted bottle and the bottom being raised up in the form of an inverted cup.

11. A single piston gas meter comprising an actuating member reciprocable by gas pressure, 20 a cam-actuating rod movable by said member, a gas-admission valve adapted to be connected to a source of gas under pressure, a gas exhaust valve, a pair of cams having generally oval-shaped grooves mounted at opposite sides of said rod and movable therewith, means for passing gas 25 from said gas-admission valve alternately to opposite sides of said actuating member to reciprocate the same, a valve-actuating rod for the gas exhaust valve, a valve-actuating rod for said gas-admission valve adapted to operate said 30 gas-admission valve to cause gas to be passed to one side or the other of said actuating member, the actuating rod for the gas-admission valve having a lug extending into the groove of one of said cams, the actuating rod for the gas exhaust valve having a lug extending into the groove of the other of said cams, whereby said valve rods are reciprocated as said cams reciprocate during movement of said actuating member, said valve rods during operation of the meter being 40 actuated in opposite directions, and means for moving the lugs of said valve rods into alternate sides of said grooves as they approach the ends thereof.

12. A single piston gas meter comprising an actuating member reciprocable by gas pressure, 45 a cam-actuating rod movable by said member, a gas-admission valve adapted to be connected to a source of gas under pressure, a gas exhaust valve, a pair of cams having generally oval-shaped grooves mounted at opposite sides of said rod and movable therewith, means for passing gas 50 from said gas-admission valve alternately to opposite sides of said actuating member to reciprocate the same, a valve-actuating rod for the gas exhaust valve, a valve-actuating rod for said gas-admission valve adapted to operate said gas-admission valve to cause gas to be passed to one side or the other of said actuating member, the actuating rod for the gas-admission valve 60 having a lug extending into the groove of one of said cams, the actuating rod for the gas exhaust valve having a lug extending into the groove of the other of said cams, whereby said valve rods are reciprocated as said cams reciprocate during movement of said actuating member, said valve rods during operation of the meter being actuated in opposite directions, means for moving the lugs of said valve rods into alternate sides of said grooves as they approach 65 the ends thereof, an indicator, and means operable by the reciprocation of said cam-actuating rod for operating said indicator.

13. A single piston gas meter comprising a bell, a bell rod fixed to said bell, a bracket fixed to said 75

- bell rod, a pair of grooved cams carried by said bracket at opposite sides thereof, a gas-admission valve, a gas exhaust valve, a reciprocatory rod for actuating each of said valves, said valve rods being operated respectively by said cams, a conduit connecting said valves to the space beneath said bell, means for passing gas from said gas-admission valve alternately to the space above said bell and through said conduit to the space beneath said bell to impart a reciprocatory movement to said bell, the gas beneath said bell being forced back through said conduit to the gas-exhaust valve as the bell descends, the actuating rod for the gas-admission valve having 10 a lug extending into the groove of one of said cams, the actuating rod for the gas-exhaust valve having a lug extending into the groove of the other of said cams, whereby said valve rods are reciprocated as said cams reciprocate during 15 movement of said bell, said valve rods during operation of the meter being actuated in opposite directions, and means for moving the lugs and said valve rods into alternate sides of said grooves as they approach the ends thereof.

20 14. A single piston gas meter comprising a bell, a bell rod fixed to said bell, a bracket fixed 25 to said bell rod, a pair of grooved cams carried by said bracket at opposite sides thereof, a gas-admission valve, a gas exhaust valve, a reciprocatory rod for actuating each of said valves, said valve rods being operated respectively by said cams, a conduit connecting said valves to the space beneath said bell, means for passing gas from said gas-admission valve alternately to the space above said bell and through said conduit to the space beneath said bell to impart a reciprocatory movement to said bell, the gas beneath said bell being forced back through said conduit to the gas-exhaust valve as the bell descends, the actuating rod for the gas-admission valve having a lug extending into the groove of one of said cams, the actuating rod for the gas-exhaust valve having a lug extending into the groove of the other of said cams, whereby said valve rods are reciprocated as said cams reciprocate during movement of said bell, said valve rods during operation of the meter being actuated in opposite directions, and spring means for moving the lugs of said valve rods into alternate sides of said grooves as they approach the ends thereof.
